UNITED STATES PATENT OFFICE

2,506,950

AUTOMATIC STEAM ELECTRIC SADIRON

Louis S. Butman, Merkel, Tex.

Application October 1, 1945, Serial No. 619,601

2 Claims. (Cl. 38—77)

1

My invention relates to an automatic steam electric sad iron, more particularly to a sad iron for ironing clothes or the like having steam generating means therein for dampening the clothes while ironing the same, and the objects of my invention are:

First, to provide a sad iron of this class which steams clothing while ironing the same, thereby saving time normally spent in sprinkling the clothes before ironing.

Second, to provide a sad iron of this class having control means for regulating the amount of steam issued through the sole plate thereof for various fabrics;

Third, to provide a sad iron of this class having a novel steam chamber heated by the heating elements of said sad iron for efficiently dampening the clothing being ironed;

Fourth, to provide a sad iron of this class in which the steam chamber is very rapidly heated providing quick starting of the steam issuing from the ports in the sole plate of said sad iron;

Fifth, to provide a sad iron of this class in which the steam chamber supply tube is drained of its supply of water when said iron is placed upon the stand in a vertical position;

Sixth, to provide a sad iron of this class having novel steam manifolds cast in the sole plate thereof; and

Seventh, to provide a sad iron of this class which is very simple and economical of construction, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon forming a part of this application in which:

Figure 1 is a longitudinal vertical sectional view of my automatic steam electric sad iron showing parts and portions in elevation to facilitate the illustration; Fig. 2 is a plan sectional view taken from the line 2—2 of Fig. 1 showing the steam chamber cover omitted and showing portions broken away to amplify the illustration; Fig. 3 is a bottom view of my automatic steam electric sad iron and Fig. 4 is a plan view thereof of showing a portion of the handle broken away exposing the valve control knob.

Similar characters of reference refer to similar parts and portions throughout the several views of the drawings:

The sole plate 1, reservoir 2, handle 3, shell 4, steam chamber 5, steam manifold 6, steam ports 7, heating elements 8, valve 9, tubes 10 to 13 inclusive, reservoir plug 14, valve control knob 15, electrical cord 16 and the steam chamber cover 17 constitute the principal parts and portions of my automatic steam electric sad iron.

10 The sole plate 1, as shown in Fig. 1 of the drawings is a cast member substantially in the form of the conventional flat iron sole plate and is provided with a tubular steam manifold fixed therein consisting of three tubes 6, as shown in Fig. 2 of the drawings communicating at the front portion of the sole plate 1 with the tube 13. This steam manifold 6 is cast in the sole plate 1 and communicating with the interior of this steam manifold 6 are the ports 7 which are arranged to issue steam from the interior of the steam manifold 6 to the bottom surface of the sole plate 1. It will be here noted that these ports 7 may be all tubular members connected to the steam manifold 6 and communicating with the interior thereof, or they may be drilled holes in the sole plate 1 and tubes 6, as desired.

15 The tube 13 communicating with the steam manifold 6 is connected in communicative relation with the steam chamber 5 which is substantially square in cross section structure arranged in U-shaped form, as shown in Fig. 2 of the drawing.

20 It will be noted that the tube 13 communicates with one end of the U-shaped steam chamber 5 while the tube 10 communicates with the interior thereof near the opposite end. The tube 10 in connection with the valve 9 is arranged to supply metered water to the interior of the steam chamber 5.

25 The valve 9 is a substantially conventional valve and is supplied water by the tube 12 which extends into the reservoir 2 and downwardly near to the bottom thereof whereby water may be drained from the bottom reservoir to a level contiguous with the bottom of the steam chamber 5.

30 Communicating with the interior of the steam chamber 5 near the opposite end from the connection of the tube 13 is a tube 11. This tube 11 is a steam equalizer tube extending to the upper portion of the reservoir 2 for equalizing the pressure of the steam in the steam chamber 5 with the water in the reservoir 2.

35 It will be noted that the angular relationship of the tube 10 relatively to the steam chamber 5 permits the drainage of water backwardly into

the reservoir 2 when the iron is placed in a substantially vertical position when not in use.

When in operation the upper end 11a of the tube 11 is normally above the water level whereby the pressure of the steam in the steam chamber 5 is conducted to the upper surface of the water in the reservoir 2 equalizing the back pressure through the valve 9 and connected tubes 10 and 12.

As shown in Fig. 1 of the drawings, the heating element is disposed between the sole plate 1 and the steam chamber 5 which is covered by the steam chamber cover 17. This heating element 8 is a substantially conventional flat Nichrome wire heating element wound on mica sheets and is properly insulated from the sole plate 1 by a sheet of mica on one side and is also insulated from the steam chamber 5 by a sheet of mica on the other side.

The diverging tubes of the steam manifold 6, as shown in Fig. 2 of the drawing conform to the rows of ports 7, as shown in Fig. 3 of the drawings, wherein the ports 7 which issue steam from the bottom of the sole plate 1 are arranged in three rows converging toward the forward end of the sole plate 1, all as shown best in Figs. 2 and 3 of the drawings.

As shown in Figs. 1 and 4 of the drawings, the valve control knob 15 is provided to operate the valve 9 for regulating the needed amount of water passing into the steam chamber 5 sufficient to dampen various fabrics. The electric cord 16 passes out of the shell 4 at one side of the handle 3, all as shown best in Fig. 4 of the drawings.

Though I have shown and described a particular construction, combination and arrangement of parts and portions, I do not wish to be limited to the particular construction, combination and arrangement but desire to include in the scope of my invention, the construction, combination and arrangement substantially as set forth in the appended claims.

Having thus described my invention, what I claim as new and desire to secure by Letters Patent is:

1. In a sad iron of the class described, the combination of a sole plate, a steam manifold cast into said sole plate having three diverging portions extending from the forward end of said sole plate, port means in said sole plate communicating with the interior of said steam manifold and the lower surfaces of said sole plate, a heating element positioned at the upper side of said sole plate, a steam chamber in the form of a rectangular in cross section U-shaped member having enclosed ends and having its middle portion adjacent the forward apex portion of the sole plate,

a tube extending from one end of said manifold to one end of said steam chamber, the apex of said steam chamber being located over the point of juncture of the portions of said manifold, said manifold comprised of a middle portion and two outer portions which lie under the legs of said U-shaped steam chamber, another tube connected near the opposite end of said steam chamber and communicating with the interior thereof, a valve in connection with said second mentioned tube and a water reservoir communicating with said valve.

2. In a sad iron of the class described, the combination of a sole plate, a steam manifold cast into said sole plate having three diverging portions extending from the forward end of said sole plate, port means in said sole plate communicating with the interior of said steam manifold and the lower surfaces of said sole plate, a heating element positioned at the upper side of said sole plate, a steam chamber in the form of a rectangular in cross section U-shaped member having enclosed ends and having its middle portion adjacent the forward apex portion of the sole plate, a tube extending from said steam manifold to one end of said steam chamber, the apex of said steam chamber being located over the point of juncture of the portions of said manifold, said manifold comprised of a middle portion and two outer portions which lie under the legs of said U-shaped steam chamber, another tube connected near the opposite end of said steam chamber and communicating with the interior thereof, a valve in connection with said second mentioned tube, a water reservoir communicating with said valve, and a pressure equalizer tube communicating with the interior of said steam chamber and the uppermost portion of said water reservoir.

LOUIS S. BUTMAN.
